UNITED STATES PATENT OFFICE.

GEORGE H. WHITTINGHAM, OF BALTIMORE, MARYLAND.

AUTOMATIC RESISTANCE-REDUCING DEVICE.

SPECIFICATION forming part of Letters Patent No. 656,004, dated August 14, 1900.

Application filed December 4, 1897. Serial No. 660,743. (No model.)

To all whom it may concern:

Be it known that I, GEORGE H. WHITTINGHAM, a citizen of the United States, residing at Baltimore, in the State of Maryland, have 5 invented certain new and useful Improvements in Automatic Resistance-Reducing Devices, of which the following is a specification.

This invention relates to an automatic starting device for electric motors of that class 10 wherein a resistance in the circuit of the motor is gradually reduced by cutting out the coils of resistance one after the other from that of the greatest resistance to that of the least resistance. Letters Patent of the United 15 States No. 499,769, granted me June 20, 1893, show a mechanism comprising a compound solenoid-magnet wherein a coarse-wire low resistance is used when starting the motor and a fine-wire high resistance while the motor is in operation. In my present invention a low-resistance heavy current is also first used and then a high-resistance small current; yet the method of employing these currents by my present invention is radically different 20 from that disclosed in my former patent. In the patent referred to there is a rigid connection between the movable resistance-controlling shoe and the armature of the solenoid-magnet. In my present invention the heavy 25 current passes through the coil around the magnet only for the very brief period that is required to raise the weight whereby the power is stored which subsequently operates the resistance-cutting-out device. This cutting-out device is then operated by such stored 30 power without any further current passing through the coils of the magnet, which affords advantages that are obvious.

The invention is illustrated in the accompanying drawings, in which—

Figure 1 is a diagrammatic view showing the circuits. Fig. 2 shows my invention of a weight interposed in the connection between the controlling-shoe and core of the magnet. 45 Fig. 3 is a similar view showing a modification. Fig. 4 is a view separately of the armature or core of the solenoid used in the modification.

The letter A designates the solenoid-magnet 50 wound with two coils, the coarse-wire low-resistance coil b and the fine-wire high-resistance coil c. The armature or core d is

movable in and out of the magnet, and on top of the magnet is an iron cap e, which serves as a magnet to retain the armature or core d 55 when the latter has been drawn up. An arm or lever F is pivoted at one end f, and its free end carries a shoe g, which is moved over the insulated plates h' h¹³ of the rheostat placed in an arc of a circle. When the motor is at rest, 60 the shoe g of the resistance-arm is in contact with a plate h, adjoining the first or high-resistance plate h'. A dash-pot governor J has its lower end pivoted at k, so as to allow slight oscillatory movement to its upper end 65 to accommodate the curved movement of the jointed connection l of the piston-rod m, which projects out of the upper end of the dash-pot.

The main-line wire is designated n n', and 70 a switch c makes connection therefrom to the motor-circuit through wire p to the pivoted resistance-arm F, plate h, wire g, to the coarse-wire coil b on the magnet, to wire p' to the first plate h' of the rheostat, to wire p², to the 75 motor Q, and then through wire p³ to the switch and to the main line. The second or fine-wire coil c on the magnet is supplied with current by wire r branching from wire p, and then the small current passes from the coil c 80 to wire r', to the field s, to wire p³, and back to the switch. This small current is always flowing through the circuit just described, r c r' s p³, and keeps the iron cap e and core d magnetized, and thereby the said armature 85 or core is held in the up position, and the resistance-arm F is also thereby held up, thus keeping the shoe g on the rheostat at the point of least resistance while the motor is running.

The operation is as follows: When the current is first turned on by the switch o, it flows to the two coils of the magnet by both circuits, the small current by the wire r and the heavy current by the arm F. The heavy current causes the armature or core d to move 95 instantly upward, thereby storing the power hereinbefore referred to by, in the construction shown in Fig. 1, extending or stretching the spiral spring I, the tension of which spring constitutes the stored-up power. The dash-pot or governor J offers resistance to the quick movement of the governor-plunger m', and consequently the resistance-arm F at first is held back and makes but slow move-

ment. Its first movement carries the shoe g from plate h to the first plate h' of the resistance-coil or rheostat, and thereby breaks the circuit of the heavy current from wire q to wire p' , and thus cuts out the coarse-wire coil b , which also acts as a part of the starting resistance. The further movement of the shoe gradually cuts out the remaining resistance. It will be seen that the tension of the spring 5 will draw on the resistance-arm F , and thereby the shoe carried by the said arm will move over the plates from h' to h^{13} and gradually cut out the resistance, and will then hold the arm F to the point of lowest resistance 10 I will draw on the resistance-arm F , and thereby the shoe carried by the said arm will move over the plates from h' to h^{13} and gradually cut out the resistance, and will then hold the arm F to the point of lowest resistance 15 while the motor is running.

Fig. 2 shows a combination in which a weight I , a cord i^2 , and a pulley i^3 connect the resistance-arm F and its shoe g with the armature d of the magnet and serve for storing power that will subsequently move the resistance-arm and shoe.

Figs. 3 and 4 show the same apparatus as in Fig. 1, but also shows a modification in the arrangement of the two circuits which include 20 the magnet. One feature of the modification consists in employing a special switch-arm to break the heavy-current circuit flowing to the magnet, said switch-arm being moved by the armature or core. In this modification 25 the armature or core d' has a longitudinal slot t , and a switch-arm u extends through the slot and has one end pivoted at u' . The free end of the switch-arm contacts with a terminal v' when the motor is not running 30 and at the moment of starting. When the current is turned on to start the motor, the armature or core d' is drawn instantly, and as it nears the limit of its traverse the switch-arm u will thereby be moved from the 35 terminal v' , and thus breaks the heavy-current circuit through the magnet. The operation of the other parts is the same as already 40 described for Fig. 1.

The wire-circuits are as follows: The main- 45 line wires are designated n n' , and a double-pole switch o is employed. Three terminals w w' w^2 are in position to be put in circuit by the two arms of the double-pole switch when the current is turned onto the motor- 50 circuit. A wire p connects from terminal w to the pivoted resistance-arm F . The heavy-current circuit through the solenoid-magnet is by a branch wire v from the wire p to the special switch-arm u , then to the terminal v' , 55 and by wire v^2 to the coarse-wire coil b on the magnet, then to wire v^3 , and to terminal w' at switch. The second or small-current circuit is from switch-terminal w^2 to wire x , to the fine-wire coil c on the magnet, to wire

x' , to wire v^3 , and to switch-terminal w' . A 60 branch wire q' connects at the pivot u' of the spiral arm and leads to the field s , then to wire p^3 , and to the switch-terminal w' .

I do not herein claim the combination, with 65 a rheostat arm or bar, of a spring or other resilient device for moving the same to cut out resistance, an electrical device for placing the spring under tension, and means for moving the rheostat arm or bar to cut in resistance. 70

Having thus described my invention, what I claim is—

1. In an automatic resistance-reducing device, the combination of a resistance having contact-plates; a controlling-shoe movable 75 over said contact-plates; a magnet; a heavy-current circuit including the magnet and resistance but operative through both only at the initial movement of the said controlling-shoe; a small-current circuit direct from the 80 main line and including only the magnet and field; and a spring or equivalent device to store power interposed in the connection between the movable controlling-shoe and the armature or core of the magnet, whereby 85 when starting, the heavy current passes through the magnet only for the brief period required to draw its armature or core and said current is thereby automatically broken, and the resistance is then gradually cut out 90 by the action of the stored power.

2. The combination of a motor; starting resistance for said motor; a solenoid included in the resistance-circuit; a contact-shoe engaging the resistance-plates; a spring or equivalent device to store power connecting the armature or core of the solenoid with the contact-shoe; and a governing device retarding the movement of the contact-shoe, whereby the momentary use of the starting-current 100 will store sufficient power to accomplish the subsequent removal of the starting resistance from the motor.

3. In an automatic resistance-reducing device, the combination of a resistance having 105 contact-plates; an arm pivoted at one end and at its free end carrying a controlling-shoe which moves over said plates; a solenoid included in the resistance-circuit; a weight connecting the pivoted arm and the core of 110 the solenoid; and a governing device connected with said pivoted arm.

In testimony whereof I affix my signature in the presence of two witnesses.

GEORGE H. WHITTINGHAM.
